UNITED STATES PATENT OFFICE.

FRANK K. GOODRICH AND GRAFTON WEST, OF COALTON, OHIO.

RAIL-JOINT.

1,078,093.

Specification of Letters Patent.

Patented Nov. 11, 1913.

Application filed April 1, 1913. Serial No. 758,280.

To all whom it may concern:

Be it known that we, FRANK K. GOODRICH and GRAFTON WEST, citizens of the United States, residing at Coalton, in the county 5 of Jackson, State of Ohio, have invented a new and useful Rail-Joint, of which the following is a specification.

The present invention appertains to rail joints, and aims primarily to provide a novel 10 and improved rail joint eliminating the employment of the usual fish plates and bolts.

One of the objects of the present invention is to provide novel means for interlocking the rail ends together in such a 15 manner that they may not separate longitudinally or directly sidewise, a predetermined operation being necessary to lock and liberate the rails.

Another object of the present invention is 20 to provide means for interlocking the rail ends so that they will be effectively connected to each other in order to withstand the hammering and other conditions to which the joint is subjected in use.

A further object of the present invention is 25 to provide a rail joint which shall be comparatively simple, substantial, durable, compact and inexpensive in construction, as well as convenient, serviceable and efficient 30 in its use.

With the foregoing general objects outlined and with other objects in view, which will be apparent as the nature of the invention is better understood, the present invention 35 resides in the combination and arrangement of parts and in the details of construction hereinafter described and claimed, it being understood that changes in the precise embodiment of the invention herein disclosed can be made within the scope of what 40 is claimed without departing from the spirit of the invention.

The preferred embodiment of the invention has been illustrated in the accompanying 45 drawing, wherein:

Figure 1 is a side elevation of the joint. Figs. 2 and 3 are sectional views taken on the lines 2-2 and 3-3 of Fig. 1, respectively. Fig. 4 is a perspective view of the 50 end of one rail. Fig. 5 is a view similar to Fig. 4 of the other rail. Fig. 6 is a view similar to Fig. 2, showing the manner of engaging the rails together.

In carrying out the invention, reference being had in detail to the drawing, the rail 55 ends have been designated by the numerals 1 and 2. The end of the web of the rail 1 is thickened as at 3, while the end of the web of the rail 2 is thickened as at 4, the thickened portion 3 extending for 60 a relatively long distance, while the thickened portion 4 extends only a short distance. The thickened portion 3 of the respective rail is recessed at one side, as at 5, while the thickened portion 4 of the other 65 rail is provided with an extension 6 at the same side which is adapted to fit within the recess 5. The thickened portion 3 has a longitudinal rib 7 extending along the upright wall of the recess 5 and adjoining the 70 base flange of the rail 1, the rib 7 being co-extensive with the recess or extending from the end of the rail to the outer end of the recess, while the extension 6 is provided with a complementary longitudinal channel or 75 groove 8 extending throughout its length and adjoining the lower edge, the groove or channel 8 being adapted to receive the rib 7. The bottom of the recess 5 is inclined from the base flange of the rail 1 toward the 80 rib 7, while the bottom of the extension 6 is similarly inclined or beveled from the outer side or face of the extension 6 to the inner side or toward the groove or channel 8 provided in the inner side. The inclined 85 or beveled bottom 10 of the extension is adapted to fit snugly against the inclined bottom 9 of the recess 5 when the rib 7 and the groove 8 are interengaged with each other. The upright wall of the recess 5 is 90 inclined as at 11, from the rib 7 to the tread or ball of the rail 1, the inner side or face 12 of the extension 6 being similarly inclined from the groove 8 to the top of the extension. The rail 1 is also provided with 95 a lip 13 depending from its tread, the said lip extending from the outer end of the recess 5 to a point short of the end of the rail, while the extension 6 has a portion of its outer side cut away, as at 14, to receive 100 the lip 13. The lip 13 provides a downwardly opening socket 15 adapted to receive the portion 16 provided by the cut away portion 14, the cut away portion 14 extending from the end of the extension 6 to a point 105 short of the end of the rail 2. The rib 7 is

provided with a notch 17 adjoining the end of the rail 1 or disposed between the end of the lip 13 and the end of the rail, while within the channel or groove 8, adjoining the end of the rail 2, there is provided a lug or boss 18.

From the foregoing, it will be noted that the rail ends are solid, the same being fashioned in any convenient manner.

10 In use, as above indicated, the recess 5 is adapted to receive the extension 6 to lock the rail ends together, a predetermined operation being necessary to join and separate the rails. Thus, to connect the rails, it is 15 necessary to swing the portion 16 of the extension 6 under and upwardly within the lip 13 or socket 15 provided thereby, and as the extension is swung laterally within the recess 5, the rib 7 will be received by the 20 groove 8, while the lug 18 will engage in the notch 17. When the rail ends have thus 25 been engaged together, the lip 13 will lock the extension against lateral or sidewise movement, and the lug 18 in engaging the notch 17 will lock the rail ends against longitudinal separation although, if desired, the engagement of the lug 18 and the notch 17 may be loose so as to permit the rails to expand and contract relative 30 to each other, due to atmospheric changes, without affecting the joint. The base flanges of the rails are spiked to the ties in the usual manner, it being noted that fish plates and bolts are eliminated in joining the rails 35 together, the rail ends being so locked together as to withstand the hammering and other conditions to which they are subjected in use. Conversely, the rails may be disengaged or separated, by swinging them laterally relative to each other so that the portion 16 of the extension 6 may be withdrawn 40 from within the socket 15, this causing the lug 18 to be disengaged from the notch 17, in which event, the rails are free to be separated, either longitudinally or laterally.

The ends of the treads and flanges of the rails are left plain or unencumbered, although they may be cut diagonally or scarfed if desired, and when the rails are 50 locked together, the ends of the treads and base flanges will abut together snugly.

The other advantages and features of the present invention will be apparent from the foregoing, taken in connection with the 55 drawing, it being noted that the objects have been carried out satisfactorily.

Having thus described the invention what is claimed as new is:—

1. A rail joint wherein one web is thickened and recessed at one side and wherein the other web has an extension to fit into the recess, the first mentioned rail having a lip depending from its tread and the extension having a portion to swing in back of the lip,

and the recess and extension having portions adapted to interlock when the said portion is swung in back of the lip, to restrain the rails from separating longitudinally.

2. A rail joint wherein the web of one rail is thickened and recessed at one side and wherein the web of the other rail has an extension to fit into the recess, the first mentioned rail having a lip depending from its tread and the extension having a portion to swing in back of the lip, and the first mentioned web and extension having an interlocking rib and groove, respectively.

3. A rail joint wherein the web of one rail is thickened and recessed at one side and wherein the other web has an extension to fit into the recess, the first mentioned rail having a lip depending from its tread and the extension having a portion to swing in back of the lip, the first mentioned web having a longitudinal rib along the upright wall of the recess, the extension having a longitudinal groove along its inner side to receive the rib, the rib being provided with a notch, and the extension having a lug within the groove to engage the notch.

4. A rail joint wherein the web of one rail is thickened and recessed at one side and wherein the other web has an extension to fit into the recess, the first mentioned rail having a lip depending from its tread and extending from end of the recess to a point short of the end of the rail, the extension being cut away to receive the lip and to provide a portion to swing in back of the lip, the first mentioned web having a longitudinal rib along the upright wall of the recess adjoining the base flange, the rib extending to the end of the rail and being provided with a notch adjoining the end of the rail, the extension being provided with a longitudinal groove in its inner side adjoining its bottom and adapted to receive the rib, and the extension being provided with a lug within the groove adjoining the end of the respective rail to engage with the said notch.

5. A rail joint wherein the web of one rail is thickened and recessed at one side and wherein the other web has an extension to fit into the recess, the first mentioned rail having a lip depending from its tread, the extension being cut away to receive the lip and to provide a portion to swing in back of the lip, the first mentioned web having a longitudinal rib along the upright wall of the recess and adjoining the base flange, the extension being provided with a longitudinal groove in its inner side and adjoining its bottom to receive the rib, the bottom of the recess being inclined from the base flange of the respective rail toward the rib, the bottom of the extension being inclined from its outer side toward the groove, the upright wall of

the recess being inclined from the rib to the tread of the respective rail, the inner side of the extension being inclined from the groove to the top of the extension, the rib being provided with a notch, and the extension being provided with a lug within the groove to engage the notch.

In testimony that we claim the foregoing

as our own, we have hereto affixed our signatures in the presence of two witnesses.
